UNITED STATES PATENT OFFICE.

CHARLES FRANCIS ADAMS EDDY, OF SAN BERNARDINO, CALIFORNIA, ASSIGNOR OF ONE-HALF TO BENJAMIN HAMMETT NORTON, OF NEW YORK, N. Y.

FOLDABLE BOX.

No. 876,531.

Specification of Letters Patent.

Patented Jan. 14, 1908.

Application filed November 28, 1906. Serial No. 345,513.

To all whom it may concern:

Be it known that I, CHARLES FRANCIS ADAMS EDDY, a citizen of the United States of America, residing at San Bernardino, 5 county of San Bernardino, California, have invented certain new and useful Improvements in Foldable Boxes, of which the following is a specification.

The invention relates to foldable boxes or 10 baskets intended more particularly for the transportation of eggs and other fragile articles and in which these can be separately confined.

The primary object of the invention is the 15 provision of a receptacle for receiving articles to be transported, having holding means, such as a tray or rack adapted to be automatically moved to an operative position when the receptacle is brought to an upright 20 position to receive the articles mentioned.

A further object of the invention is the provision of a receptacle which can be quickly and easily set up for use and when not in use can be folded flat for compactness 25 and easy shipment thereof in bulk. The receptacle preferably is of such character that when in position for use the parts thereof interlock and fasten in a way to make the box exceptionally secure.

30 A still further object of the invention is the provision of several trays flexibly connected to opposite walls of the box and having a plurality of openings in each tray so disposed that when the said box is brought to a 35 set up or upright position the said openings of the respective trays will register with each other to form compartments for receiving the articles within the box.

Other objects of the invention are the provision of means which is simple in construction, durable, efficient in operation, and inexpensive in the manufacture.

With these and other objects in view the invention in practice is preferably associated 45 and executed with the construction, combination and arrangement of parts hereinafter referred to and illustrated in the accompanying drawings. However, it is to be understood that changes, variations and modifications 50 may be made as come properly within the scope of the claims hereinto appended.

In the drawings:—Figure 1 is a plan view of the box or basket. Fig. 2 is a plan view of the box or basket having the cover elevated.

Fig. 3 is a sectional view on the line 3—3 of 55 Fig. 2. Fig. 4 is a transverse sectional view on the line 4—4 of Fig. 2. Fig. 5 is a perspective view of the box with the end walls and tongues interlocking, and the cover in a slightly closed position. Fig. 6 is a perspective view of the box or basket in its flat folded position. Fig. 7 is a detail view of one of the holding means detached from the box. Fig. 8 is a sectional view on the line 8—8 of Fig. 6. Fig. 9 is a modification of the box or 65 basket. Fig. 10 is a sectional view on the line 10—10 of Fig. 9; and Fig. 11 is a section on the line 11—11 of Fig. 9. Fig. 12 is a transverse sectional view of Fig. 2, showing the box or basket in the act of being folded 70 or collapsed.

Similar reference characters indicate corresponding parts throughout the several views.

In the drawings the numeral 2 designates 75 the bottom of the box or basket of any desirable shape but which is ordinarily rectangular and which has end walls, as 3, flexibly formed by crease lines 4 with the said bottom 2. Each of the said end walls is preferably 80 provided with elongated slots 5 spaced from, and extending in parallelism with, each other from the crease lines 4 within the body of said walls. At opposite side edges of the bottom 2 are shown crease lines 6 to make 85 flexibly connected side walls as 7, one of the side walls 7 is provided with a crease line 8 to form a flexibly connected cover as 9 having crease lines 10 and 11 forming flaps 12. At opposite ends of the side walls 7 are tongues 90 as 13 formed by crease lines 14 and the same are adapted to be inserted into the slots 5 in the end walls 3 when the latter are folded on the said crease lines and also the side walls 7 so as to set up the body portion of the 95 box or basket, and by interlocking engagement of the tongues with the end walls will maintain the box or basket in a set up position.

Connected to the side walls 7 are trays as 100 15 and 16, each having crease lines 17 arranged near opposite edges of the said trays and extending throughout the longitudinal extent thereof to form flexible connections 18, the latter being secured to the side walls 7 105 by adhesive material or other suitable fastening. Said trays are spaced a suitable distance from each other when connected to

the side walls 7 and are arranged in parallelism, and the tray 16 is provided with openings 20 arranged in rows throughout the area thereof and the tray 15 is provided 5 with increased openings 19. When the box or basket is being set up the trays will be automatically shifted to an operative position to bring the openings 19 and 20 in register, thereby forming compartments for receiving eggs and other analogous articles. 10 Flexibly connected to the bottom 2 at the interior face thereof are straps 21 having connection with the tray 15, which will strengthen and form a further flexible connection for the same.

In proximity to the cover 9 is a tray 22 having a plurality of openings 23 adapted to be brought in register with the openings 20 in the tray 16 when the cover 2 has been 20 brought to a closed position and for connecting the said tray 22 to one of the flaps 12 and to one of the side walls 7 at the back of the box are flexible connections 24 formed by crease lines 25 in the body of the tray 22.

25 It will be apparent that when the box or basket has been brought to a set up position and the cover having been closed, the flaps 12 will be positioned within the body at the interior of the box contiguous with the side edges formed by the end walls and side walls. 30 In the end walls are openings 26 forming air vents for the admission of air to the interior of the box. It is obvious due to the crease lines and flexible connections of the trays

35 the body of the box can be brought to a collapsed position. In Figs. 9, 10 and 11 is shown a modified form of the invention having a cover as 27 provided with crease lines 28 forming flaps as 29, and within the 40 box or basket is a continuous piece of material having crease lines 30 and 31 to provide trays as 32 and flexible connections as 33 at opposite extremities of the latter, which are glued to the interior faces of the side walls as 45 7 of the said box or basket. With this exception the remaining portion of the box or basket is identical with the construction as shown in Figs. 1 to 5. Furthermore, it will be noted, due to the flexible connections of

50 the trays and the position thereof within the interior of the box or basket, and that when the articles are placed in the compartments formed by the openings within the trays, after the box or basket has been set up, the 55 said trays will produce a cushioning effect residing in the flexibility of the same, thereby overcoming any liability of the breakage of the said articles during the handling or transportation of the box or basket.

60 The material employed in the box or basket is preferably pasteboard, however, other analogous material may be substituted therefor.

Having thus described the invention, what is claimed as new is:—

65

1. A box of knock-down formation, comprising a bottom, side and end walls, a cover, each flexibly associated to allow the collapsing of the box, a plurality of trays for supporting the contents of the latter, and each 70 having connection with both of said opposite side walls thereof which permit said trays to collapse within the box, and a tray having connection with one side wall and with the cover, the intermediate tray having openings 75 and the remaining trays also provided with decreased openings with respect to the openings in the intermediate tray for supporting articles.

2. A foldable egg box comprising a bottom, 80 cover, side and end walls, each flexibly associated to allow the collapsing of the box, and a plurality of superposed perforated trays, each formed of one continuous piece of material and having crease lines near opposite side 85 edges thereof to provide flexible means bent at right angles to the said trays for connection with the opposite side walls of the box to hold the trays spaced from each other and to allow the same to automatically collapse 90 within the said box, the intermediate tray having increased perforations with respect to the perforations in the remaining trays to correspond to the larger diameter of the eggs, the latter being suspended and out of contact 95 with the said box.

3. A knock-down box comprising a body of one piece of material forming a bottom, top, side and end walls, and superposed perforated trays having opposite flexible connection with the side walls of the box which 100 permit the same to automatically collapse within the latter.

4. A knock-down box having a bottom, top, side and end walls, normally collapsed, 105 and perforated trays flexibly connected to the interior face of the said side walls and adapted to be automatically shifted to superposed horizontal position when the side walls of the box are moved at right angles to the 110 bottom of the latter.

5. A knock-down box having a normally folded body, and perforated trays flexibly secured to the body at the interior of the same and automatically shiftable to superposed relation with respect to each other when the said body of the box is erected to operative position for receiving its contents.

In testimony whereof I have hereunto set my hand in presence of two subscribing witnesses.

CHARLES FRANCIS ADAMS EDDY.
